FOREIGN PATENT DOCUMENTS

JP 2012206228 A * 10/2012

Primary Examiner — Patricia A Palasik

(74) Attorney, Agent, or Firm — Schott, P.C.

(57) **CLAIM**

The ornamental design for a milling tool, as shown and described.

DESCRIPTION

1. Milling tool

1.1 : Top

1.2 : Left

1.3 : Bottom

1.4 : Perspective

1.5 : Perspective

1.6 : Enlarged

The design relates to a milling tool for a pipe.

1 Claim, 6 Drawing Sheets
